INVENTOR

UNITED STATES PATENT OFFICE.

WALTER KENNEDY, OF BELLEVUE, PENNSYLVANIA.

BLAST-FURNACE APPARATUS.

No. 884,865.

Specification of Letters Patent. Patented April 14, 1908.

Application filed May 24, 1907. Serial No. 375,546.

To all whom it may concern:

Be it known that I, WALTER KENNEDY, residing at Bellevue, in the county of Allegheny and State of Pennsylvania, a citizen 5 of the United States, have invented or discovered certain new and useful Improvements in Blast-Furnace Apparatus, of which the following is a specification.

The invention described herein relates to 10 certain improvements in charge distributing apparatus for blast furnaces, and has for its object a construction whereby the charge may be uniformly distributed in the furnace and the seal of the furnace may be maintained while the main bell is open for dropping the charge.

The invention is hereinafter more fully described and claimed.

In the accompanying drawings forming a 20 part of this specification, Figure 1 is a sectional elevation of the upper portion of a blast furnace having my improved charging apparatus arranged thereon; Fig. 2 is a sectional plan view indicated by the line II—II 25 Fig. 1; Fig. 3 is a view partly in section and partly in elevation, illustrating a modification of the charging apparatus shown in Fig. 1.

In the practice of my invention, the main 30 hopper 1 is secured to the furnace in the usual or any suitable manner, and is provided at or near its upper end with an inwardly projecting ledge 2 designed to form a seat for an auxiliary distributing hopper 3. As shown in Figs. 1 and 3, this ledge 2 is 35 preferably provided with a rounded seat for the reception of the correspondingly shaped rib 4 on the auxiliary distributing hopper, so that the latter may move easily around on its seat. The main distributing hopper 5 is 40 located above the auxiliary hopper and preferably supported on the main hopper, it being provided with a horizontal flange 6 adapted to rest upon a seat 7 formed on the 45 upper end of or supported by the main hopper. In order to facilitate the rotation of the distributing hoppers as hereinafter described, anti-friction rollers 8 are arranged between the flange 6 and the seat 7. As 50 shown the lower end of the main distributing hopper projects down into the upper end of the auxiliary distributing hopper so that one is practically a continuation of the other. In order that the auxiliary hopper may 55 rotate with the main distributing hopper they are interlocked, preferably by means of suit-

ably spaced lugs or teeth 11 and 12 on the two hoppers. In order to rotate these hoppers, a ring 13 is supported by the seat 7 on the main hopper and provided around its 60 periphery with teeth for engagement with the rack 14 adapted to be reciprocated by the fluid-pressure cylinder 15. Pawls 16 are mounted on the ring 13 and engage teeth on the periphery of the flange 6 of the 65 distributing hopper. In this construction the ring 13 is given a reciprocating movement which is changed into a step by step onward movement of the distributing hoppers. In this construction, as will be readily 70 understood by those skilled in the art, the weight of only a small portion of the charge will rest upon the auxiliary distributing bell, so that the latter will not present much resistance to the rotation of the main distributing hopper. The principal load will 75 be borne by the main distributing hopper as in the construction heretofore used. The main or principal use of the auxiliary hopper is to maintain a gas seal at all times when the 80 distributing hopper is being rotated.

In the construction shown in Fig. 3, provision is made for exerting an upward pressure on the main distributing hopper when the latter is being rotated, thus reducing the 85 frictional resistance to its movement. The toothed ring is mounted as heretofore stated on seat 7 of the main bell and is adapted to be reciprocated by the fluid pressure cylinder. In the upper face of this toothed ring 90 are formed a series of teeth with which pawls 17 pivotally mounted on the distributing hopper will engage. The arrangement of these pawls is such that when the ring is rotated an upward or lifting force will be 95 exerted on the distributing hopper, facilitating its rotation.

I claim herein as my invention.

1. A blast furnace charging apparatus having in combination a main hopper and bell, main and auxiliary distributing hoppers in driving engagement with each other, the auxiliary hopper having a gas-tight seat on the main hopper, means for rotating the main distributing hopper, and means for 100 closing the auxiliary hopper.

2. A blast furnace charging apparatus having in combination a main hopper and bell, main distributing and auxiliary distributing hoppers in driving engagement with each other, the auxiliary hopper having a gas-tight seat on the main hopper, means 105

for closing the auxiliary hopper, means for reducing the friction between the main hopper and the auxiliary hopper, and means for rotating the main distributing hopper.

5. 3. A blast furnace charging apparatus having in combination a main hopper and bell, a distributing hopper seated on the main hopper, a ring concentric with the axis of the hoppers, means for shifting said ring around its axis, pawls interposed between the ring and distributing hopper whereby said hopper may be shifted by the ring, and means for closing said hopper.
10. 4. A blast furnace charging apparatus

having in combination a main hopper, a distributing hopper seated on the main hopper, a toothed ring concentric with the axis of the hoppers, pawls depending at an angle from the distributing hopper into engagement with said ring, means for reciprocating said ring, and means for closing the hoppers. 15

In testimony whereof, I have hereunto set my hand.

WALTER KENNEDY.
